UNITED STATES PATENT OFFICE.

CHARLES RICHARD FAIREY, OF HAYES, ENGLAND.

AEROPLANE.

1,337,762.

Specification of Letters Patent. Patented Apr. 20, 1920.

Application filed April 23, 1919. Serial No. 292,163.

To all whom it may concern:

Be it known that I, CHARLES RICHARD FAIREY, a subject of the King of Great Britain, and resident of Cranford Lane, 5 Hayes, in the county of Middlesex, England, have invented a certain new and useful Improvement in Aeroplanes, of which the following is a specification.

This invention relates to the control, at 10 will, of the lateral stability of aeroplanes or flying machines which are supported, partly or wholly, by two or more surfaces or planes superimposed one above another and of equal or approximately equal lateral span. 15 For the sake of clearness, the following terms used in this description will be employed in the sense now to be explained. Each complete plane, extending as a whole from side to side of the machine, will be 20 called a "deck", and the two half-planes (upper and lower) at one side of the center of the machine will, taken together, be called a "wing"; the machine being regarded as having a right and a left "wing" 25 each comprising an upper and a lower "plane" (in reality an upper and a lower half-plane or half-deck). The outer or lateral extremity of a wing will be called the "tip" of that wing, and similarly the outer 30 or lateral extremity of each (half-) plane comprised in a wing will be called the "tip" of that plane. The "gap" is, as usual, the vertical distance separating the two half-planes which together constitute a wing, 35 more particularly toward its outer lateral extremity or tip. An "aileron" is, as usual, a small angularly-movable plane, either independent of both decks or hinged to an upper or a lower deck toward the tip of each 40 wing, and capable of having its inclination varied without of necessity "warping" either plane of the wing itself. In some cases an aileron is separate from, and placed in the gap between, the upper and lower 45 planes; but in this description (unless where otherwise stated) an aileron is to be understood as being a hinged portion or extension of the rearward margin of an upper or a lower plane at or toward its tip; ailerons being, as is well known, of two kinds, single- 50 acting and double-acting. A single-acting aileron is capable of being depressed at will below its normal inclination, the aileron being pulled down positively by the pilot, but 55 returned to its normal inclination automatically either by wind-pressure or by spring-

power when the pull is released. A double-acting or so-called "balanced" aileron is capable of being, at will, either depressed or raised beyond its normal inclination, such 60 an aileron being in one arrangement depressed positively by the pilot against spring-power constantly tending to raise it above its normal inclination, and being in another arrangement pulled downward below or upward 65 above its normal inclination, as required, and also restored to its normal inclination, in each case positively by the pilot.

Assuming the machine to have canted laterally so that one wing has dropped below 70 the level of the other, the depression of an aileron of what for the time being is the lower wing will tend to lift that wing, for the reason that its immediate effect will be to increase the lifting power of that plane 75 of the wing to which the aileron appertains. But, as this increased lifting power involves an increase in the head-resistance offered by the plane in question, the speed of the forward movement of the lower wing (whereof 80 said plane forms part) will be reduced, with a corresponding diminution of the otherwise increased lifting power of the wing. At the same time, unless means are adopted to alter it, the head-resistance offered by the 85 planes of the opposite or higher wing of the machine may remain approximately at its original value, with the result that, the speed of the forward movement of said higher wing continuing undiminished, the 90 machine as a whole will tend to swerve from the straight course toward that side at which the (for the time being) lower, and slower, wing is situated.

Several methods of effecting, at will, lateral control in such circumstances, have been proposed for machines having upper and lower decks of equal or approximately equal span. Thus, for example, it has been proposed to fit ailerons to the upper plane alone. 95 But in this case, it is found that the attempt to lift the (for the time being) lower wing of the machine by depressing its aileron has the opposite of the desired effect if the aileron be depressed beyond a very limited 100 range, for the reason that the partial closing of the gap at the lower side of the machine (consequent on excessive depression of the aileron) causes such an increase in the head-resistance offered by the wing at that side of 105 the machine that this wing is slowed-up and its lifting power is either insufficiently in-

creased or is even reduced; the defect being due to the fact that the head-resistance of the respective wings is not equalized as is necessary for lateral stabilization apart 5 from control of the direction of flight.

Efforts to overcome this defect by enlarging the chord of the upper deck have not proved successful, and the usual practice has been either to extend the upper deck 10 laterally, fitting an aileron to each lateral extension (as in certain well known systems of construction), or to fit ailerons to both the upper and lower decks when these are of equal or approximately equal lateral span 15 (as in other well known systems). In this connection it is to be observed that, in cases where an aileron, separate from both the upper and lower decks, is placed in each gap, the general opinion is that equalization of 20 the head-resistance of the respective wings is obtained for only one angle of attack, so that, as this angle is subject to continual variation, equalization of head-resistance under all conditions cannot be said to have 25 as yet been completely attained by the method in question.

According to another well known system, it has been proposed to counteract the tendency to swerve, during the righting operation, toward that side at which the (for the time being) lower wing is situated, by automatically steering the machine in the horizontal direction, for which purpose a rudder has been mechanically coupled to the 30 ailerons of both wings in such manner that, on the aileron or ailerons of the (for the time being) lower wing being depressed in order to effect the lifting of that wing, the rudder is automatically moved so as to steer 35 the machine in the direction opposite to that in which it tends to swerve.

The present invention relates to aeroplanes other than monoplanes and has for its object to enable ailerons to be used for 40 the purpose of effecting lateral righting at will, in such manner that the head-resistance of the respective wings will be substantially equalized, and that moreover the employment of a rudder mechanically coupled to 45 the ailerons, for the purpose of automatically counteracting the tendency of the machine to swerve during the righting operation, will be rendered unnecessary. With this object in view, an aeroplane constructed 50 in accordance with the present invention has a double-acting aileron fitted to the lower plane alone of each wing, the decks of the machine being made of equal or approximately equal span, and the means for controlling the respective ailerons are so connected together that when the one aileron is depressed below, the other will be raised 55 above the normal inclination and vice versa; no direct mechanical interconnection between the ailerons and rudder being em-

ployed. The double-acting ailerons may either be moved wholly by the pilot, or may be depressed by the pilot against spring-power tending to raise them above their normal inclination.

With this arrangement, when the machine 70 cants laterally, righting may be effected by simply depressing the aileron of the (for the time being) lower wing, the interconnection between the ailerons having for effect to simultaneously raise the aileron of the higher wing, with the result that, while the lifting power of the lower wing is increased, the head-resistance of the respective wings is more or less equalized. As, therefore, there may be little or no tendency on the part of the machine to swerve, during the righting operation, toward that side at which the (for the time being) lower wing is situated, the pilot may find it unnecessary, 80 or scarcely necessary, to manipulate the rudder for the purpose of counteracting such tendency. In these circumstances, it will be obvious that a direct mechanical interconnection between the ailerons and the rudder 85 might even prove disadvantageous; the more so in case where (as may sometimes occur), the head-resistance of the (for the time being) higher wing happens to be increased in a higher ratio than that of the lower wing, 90 since, in such case, the machine may actually tend to swerve toward the higher side, thus rendering it advisable for the pilot to steer toward the lower instead of toward the 95 higher side during the righting operation. 100

In the accompanying drawings which illustrate diagrammatically an embodiment of this invention applied to a biplane, Figure 1 is a front elevation, Fig. 2 is a plan of the lower plane and Fig. 3 is a part side 105 view of the machine drawn to a larger scale showing the right hand wing in end elevation with its aileron depressed.

As will be seen in Fig. 1 the upper and lower planes *a* and *b* respectively are of the same length transversely of the machine and, as will be seen in Fig. 3, they have substantially equal chords. The lower plane of each wing includes in its superficial area a hinged aileron *c* extending from the wing tip inwardly through the usual distance, each aileron having secured to it two pairs of levers *d*, *e* which extend respectively upward and downward from the general plane of the aileron near its hinge *f*. Attached to the lower levers *e*, *e* of each aileron *c* are branch control cables *g*, *g* which are passed around guide pulleys *h*, *h* and unite at *j* to form a single control cable *k*, and the cables *k*, *k* of the respective ailerons *c*, *c* are led 115 around guide pulleys *m*, *m* and wound from opposite directions around a drum *n* adapted to be rotated by a hand wheel *o*. Attached to the upper levers *d*, *d* of each aileron *c* are branch control cables *p*, *p* which 120

125

are passed around guide pulleys q , q and united at r , to form a single control cable s , and the cables s , s of the respective ailerons c , c are led around guide pulleys t , t and 5 after being crossed the one over the other, as shown in Fig. 1, are attached to the control cables k , k at u , u so that when the drum n is rotated by the hand wheel o in one direction the control cable k of one aileron c is drawn upon to depress said aileron and the attached control cable s is simultaneously drawn upon to raise the other aileron c the corresponding control cables k and s of the ailerons being relaxed respectively to 10 permit such depression and raising.

I claim:—

In an aeroplane having a wing structure comprising upper and lower planes of substantially equal span positioned one directly 15 above the other, the combination with dou-

ble-acting ailerons pivotally connected to the lower plane and forming the rear portion thereof, of an independent control member and connections from said control member to each of said ailerons adapted positively 25 to bend the same downwardly to increase the camber of the lower plane, and to bend the same upwardly to decrease the camber thereof and to decrease the gap between the lower and upper planes, said connections being ar- 30 ranged to bend simultaneously one aileron downwardly and the other upwardly, whereby the increase of head resistance on one wing due to increase of wing camber is balanced by a simultaneous increase of head 35 resistance due to decrease of gap between planes on the other side, said control and connections operating independently of any rudder controls.

CHARLES RICHARD FAIREY.
